UNITED STATES PATENT OFFICE.

BENJAMIN F. SCHREIBER, OF WILLIAMSPORT, PENNSYLVANIA.

GAME.

1,161,347.

Specification of Letters Patent. Patented Nov. 23, 1915.

Application filed May 6, 1915. Serial No. 26,330.

To all whom it may concern:

Be it known that I, BENJAMIN F. SCHREIBER, a citizen of the United States, residing at Williamsport, in the county of Lycoming and State of Pennsylvania, have invented a new and useful Game, of which the following is a specification.

This invention relates to games, one of its objects being to provide a novel form of game board utilizing movable game pieces in connection with an actuating element whereby the game pieces are moved upon the board, the game pieces being so shaped that, when brought to certain positions relative to the game board, they will be caused to assume overturned positions.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the accompanying drawings the preferred form of the invention has been shown.

In said drawings: Figure 1 is a plan view of the game board, the game pieces being shown in different positions thereon. Fig. 2 is a vertical transverse section through the game board. Fig. 3 is a detail view of one of the game pieces.

Referring to the figures by characters of reference 1 designates a base which can be rectangular as shown and which has side walls 2 upstanding therefrom and adapted to be engaged by a lid or cover indicated by dotted lines at 3 in Fig. 2.

Upstanding from the base 1 is a circular wall 4 and suspended by the walls 2 between them and the circular wall 4 are wires 5 which are parallel with the walls 2. On each of these wires are strung beads 6 and 7, the beads 6 being preferably of one color, while the beads 7 are of another color. Printed or otherwise indicated upon the inner face of one of the walls 2 are the words

"The Hague peace" as shown particularly in Fig. 2, and that portion of the base 1 which is within the area defined by the wall 4, has a segment marked off, as at 8, this segment being located adjacent that wall 2 on which appear the words above quoted.

In this segment 8 appear the words "Peace zone." A block 9 is erected at the center of the space defined by wall 4 and revolvably mounted on this post is a pin 9' having a cross strip 10 extending over the wall 4 and adapted to spin. The game pieces used in connection with the board are all of the same size and shape and each includes a semi-spherical base 11 of lead or other heavy material, there being a stem 12 projecting perpendicularly from the center of the flat face of the base.

Four spots 13 are indicated on the base 1 and when the game is to be played, one of the game pieces is placed on each of these spots. As the base of each game piece is semi-spherical and made of heavy metal, it will be apparent that under ordinary conditions the stems 12 of the game pieces will extend upwardly into the path of the cross strip 10. Any number of persons may play the game. After the game pieces have been properly positioned, the beads are arranged upon the center portions of the respective wires and the first player then spins the strip 10 three times or, if preferred, the players can spin in turn. When the strip 10 is actuated it will strike the upstanding stems of the game pieces and cause said game pieces to be thrown over on their sides. They will immediately move back to their upstanding positions unless the heads of the game pieces should come against the circular wall 4, whereupon they will remain in their lowered positions. Each time a game piece is thus left in lowered position, one point is counted for the player and one of the beads 7 is moved to the end of the wire on which it is mounted. After five beads 7 have thus been shifted, one of the beads 6 is shifted to the end of the wire and the beads 7 are brought back to their normal positions.

Thus it will be seen that the points of the game can be easily counted. Should a game piece be left in its fallen position on the "peace zone" the player is entitled to move one of the beads 6 to the end of the wire. The first player getting all of his beads 6 to the end of the wire wins the game.

What is claimed is:

1. A game including a board, a circular wall thereon, the space surrounded by the wall being divided into separate zones, and a spinning element pivotally mounted at the center of said space and extending over the wall.

2. A game including a board, a circular wall thereon, the space surrounded by the wall being divided into separate zones, and a spinning element pivotally mounted at the center of said space and extending over the wall, there being spots within the space surrounded by said wall and game pieces adapted to be placed on the spots, each game piece including a semi-spherical weighted base and an upstanding stem thereon. 25
3. A game including a board, a circular wall thereon, the space surrounded by the wall being divided into separate zones, a spinning element pivotally mounted at the center of said space and extending over the wall, upstanding walls at the outer edges of the space, and a string of counters supported adjacent the inner side of each of said last mentioned walls. 30
4. A game including a board, a circular wall thereon, the space surrounded by the wall being divided into separate zones, a spinning element pivotally mounted at the center of said space and extending over the wall, there being spots within the space surrounded by said wall, game pieces adapted to be placed on the spots, each game piece including a semi-spherical weighted base and an upstanding stem thereon, upstanding walls along the edges of the board, and a string of counters supported adjacent the inner side of each of said last mentioned walls, each string of counters including two groups of beads, the beads of one group being of a color different from that of the beads of the other group. 35

In testimony that I claim the foregoing as my own, I have hereto affixed my signature in the presence of two witnesses.

BENJAMIN F. SCHREIBER.
